US0D1046279S

(12) **United States Design Patent** (10) **Patent No.:** **US D1,046,279 S**
(45) **Date of Patent:** **** Oct. 8, 2024**

(54) **ELECTRONIC CIGARETTE**

(71) Applicant: **SHENZHEN WOODY VAPES TECHNOLOGY CO., LTD.**, Shenzhen (CN)
(72) Inventors: **Jinlong Cai**, Shenzhen (CN); **Shihua Chen**, Shenzhen (CN); **Bozhong Li**, Shenzhen (CN); **Junyuan Fan**, Shenzhen (CN)

(**) Term: **15 Years**

(21) Appl. No.: **35/521,151**

(22) Filed: **Apr. 12, 2024**

(80) **Hague Agreement Data**

Int. Filing Date: **Apr. 12, 2024**

Int. Reg. No.: **DM/237299**

Int. Reg. Date: **Apr. 12, 2024**

Int. Reg. Pub. Date: **Jun. 7, 2024**

(30) **Foreign Application Priority Data**

Jan. 15, 2024 (CN) 202430024839.3

Assistant Examiner — Karen M. Jones

(57) **CLAIM**

The ornamental design for an electronic cigarette, as shown and described.

DESCRIPTION

1. Electronic cigarette

1.1 : Front

1.2 : Back

1.3 : Left

1.4 : Right

1.5 : Top

1.6 : Bottom

1.7 : Perspective

1.8 : Perspective

1.1 is a front view of an electronic cigarette showing our new design; 1.2 is a rear view thereof; 1.3 is a left view thereof; 1.4 is a right view thereof; 1.5 is a top view thereof; 1.6 is a bottom view thereof; 1.7 is a front, top and right side perspective view thereof; and 1.8 is a front, bottom and left side perspective view thereof; The color deviations among the reproductions are due to shadow or light reflections.

1 Claim, 8 Drawing Sheets
